UNITED STATES PATENT OFFICE.

ERNEST G. SCHREYER, OF CHICAGO, ILLINOIS.

TOY.

1,423,035.

Specification of Letters Patent. Patented July 18, 1922.

Application filed December 13, 1919. Serial No. 344,580.

To all whom it may concern:

Be it known that I, ERNEST G. SCHREYER, a citizen of the United States, residing at Chicago, in the county of Cook and State of Illinois, have invented certain new and useful Improvements in Toys, of which the following is a specification.

My invention relates to toys and has for its primary object the provision of a novel 10 toy embodying improvements in construction and arrangement whereby the relative skill of several players is determinable. Another object is the provision of an improvement in hand operated toys for simulating a 15 race between vehicles driven by the respective players.

Other objects and advantages of the invention will appear from the following description, taken in conjunction with the accompanying drawings which form a part of this specification and illustrate the preferred embodiment of the invention.

In the drawings:

Fig. 1 is a top plan view of the invention. 25 Fig. 2 is a section taken approximately on line 2—2 of Fig. 1.

Fig. 3 is a fragmentary section on line 3—3 of Fig. 1.

Fig. 4 is a fragmentary plan view of one 30 corner of the invention with the deck removed to expose parts below.

Fig. 5 is a front elevation of a counter and its casing forming part of this invention.

35 Fig. 6 is a plan view of the parts shown in Fig. 5.

Fig. 7 is a side elevation and Fig. 8 a top plan view illustrating the adaptability of the invention as a table.

40 The invention comprises a box like structure generally indicated at 10 and including an imperforate bottom 11, side walls 12 and a deck 13. The latter is pierced by a plurality of endless slots 14 each shaped like an 45 elongated race track and paralleling the others. Those portions 15 of the deck enclosed by the slots are each supported on a vertical riser 16 rigidly fixed along its lower edge to the bottom 11.

50 At the center end curve of the forward end of each slot 14 a vertical spindle 17 has its upper and lower ends respectively journaled in the deck portion 15 and the bottom 11, and a similar spindle 18 is journaled in like manner at the rear end of each slot 14. A sprocket wheel 19 is fixed upon

spindle 17 and an identical sprocket wheel 21 is fixed on spindle 18, these sprockets being of such radius as to cause the teeth of each to rotate directly below the respective 60 semi-circular ends of the slot 14. Applicant has illustrated in Fig. 1 an embodiment of his toy containing four of the race track slots 14, but it will be obvious from the further description that a toy may be built with 65 any number of slots desired. A vertical crank shaft 22 is journaled in the bottom 11 and deck 13 near each spindle 17 and carries the spindle wheel 23 which, by means of a chain 24, is connected to a sprocket pinion 70 25 fixed on spindle 17. Preferably pinion 25 has less teeth than sprocket 23 so that it turns faster than the latter. An endless chain 26 connects the sprockets 19 and 21, and by rotation of a hand crank 27 keyed to 75 shaft 22, the chain 26 and spindle 18 are rotated. By means of brackets 28 upstanding stiffly from chain 26, and projecting above the deck through the slot 14, a miniature object such as a small automobile 29 depicted 80 in Figs. 1, 2 and 3, is fixed with relation to the chain and travels above the deck portions 13 and 15 through a path defined by the slot 14. If desired, the image of a race horse or any other suitable object may be 85 substituted for the miniature automobile 29. Oppositely positioned standards 31 and 32 rise from the deck 13 near opposite sides thereof and, on their in-turned faces, are each vertically slotted as at 33 to provide a 90 guideway for a block 34. One of these blocks is fixedly connected near each end of a signal rod 35, and each extremity of the rod is normally upheld by bearing upon a trigger 36 pivoted as at 37 within a hollow 95 standard. Pivotal movement of trigger 36 in a direction outwardly of the deck 13 permits rod 35 to drop into close proximity with the automobile 29 travelling along the deck; this latter position of the signal rod 100 105 being indicated in dotted lines in Figs. 2 and 3.

Within the structure 10, near and paralleling the rear wall thereof are mounted two spaced bearing brackets 38 and 39 which also 110 parallel the deck 13 just below the latter. These bars extend across the ends of all the slots 14 but are positioned rearwardly of those slots. Spaced back of each spindle 18 is a vertical driving shaft 41 having its upper and lower ends respectively journaled in the bracket 39 and bottom 11. By means

of a pinion 42 on spindle 18 and a meshing gear 43 on the driving shaft, the latter is rotated from the spindle, the pinion being much slower than the gear in order to reduce the speed of the driving shaft with respect to that of spindle 18. A thrust bar 44 traverses the rear portion of structure 10 and is pivotally connected and partially supported from bracket 39 by means of four parallel links respectively numbered from 45 to 48 inclusive. One of these links is provided for each slot 14 and its associated mechanism. For each slot 14 there is provided in connection with the heretofore described associated mechanism, a counter shaft 49 driven from the driving shaft 41 by means of a pinion 51 on the driving shaft and a relatively larger gear 52 on the counter shaft. A stud 53 projects upwardly from gear 52 into the level of the link 45, or 46 to 48, as the case may be. Obviously the reduction of gear herein described results in a very slow rotation of stud 53 about the counter shaft 49 with respect to any given rotation of crank shaft 22 and spindle 17.

That end of thrust bar 44 nearest standard 31 is pivoted to the rear end of a trigger lever 54 fulcrumed on a pivoted axis 55, the opposite end of this lever being positioned to trip the trigger 36 of standard 31 when bar 44 is moved in the direction indicated by arrow 56 in Figs. 1 and 4. The trigger in standard 32 is simultaneously tripped by such movement of bar 44 through the medium of a similar but shorter trigger lever 57 fulcrumed on a pivotal axis 58 and having its rear end slotted for pivotal engagement at 59 with a reversing lever 61 which is fulcrumed at 62 and has its rear end pivoted to bar 44. Clockwise rotation of cranks 27 produces much slower rotation of studs 53 in the same direction as indicated by arrows 63 in Fig. 4, so that one of these studs finally strikes its link 45, 46, 47 or 48 and swings the link in a counter-clockwise direction about the pivot 64 which connects the forward end of each link with bracket 39. Such movement of any one of the links 45-48 shifts the bar 44 in the direction of arrow 56, trips triggers 36, and results in the dropping of signal bar 35. This movement of link 45 is depicted in Fig. 4 by the dotted line position of that stud 53 associated with link 45 and by the dotted center line 65 shown for that link: the consequent swing of trigger lever 54 is indicated by dotted center line 66 in that figure: and the resulting oscillation of trigger 36 is indicated by a dotted center line 67 in Fig. 3. Of course when any given stud 53 strikes and moves its associated link, all of the links 45-48 swing in synchronism with bar 44.

Each countershaft 49 projects above deck 13 and there carries a counting wheel 68 which is marked on its periphery with a zero

and the consecutively arranged digits 1 to 9. A cover 69 encloses each number wheel and is pierced by a forwardly exposed window 71 through which a single digit is exposed at a time. Preferably the digits are so placed on wheel 68 that "1" is visible through each window 71 when each stud 53 is in the rear half its circular path and near its link 45, 46, 47 or 48, and when all of the automobiles 29 are similarly positioned with relation to their respective race-track-shaped slots 14.

In the operation of the invention, and with the parts all arranged as last above described, the trigger tripping levers, thrust bar and links are set as shown in full lines in Figs. 3 and 4, and the signal bar 35 is mounted upon the triggers 36 as shown in full lines in Fig. 3. The toy is designed for operation by several players, one for each crank handle 26. At a given sign each player grasps his crank handle and rotates in a clockwise direction at his utmost speed, this rotation being continued until that stud 53 driven by the most rapid player strikes its link and causes the signal bar 35 to drop. The players immediately stop turning and the apparatus is again set for play. After every play each player's score, as indicated by the digit appearing in windows 71, is set down in a separate column and, after a predetermined number of plays, the relative skill of the players is determined by the totals of these columns. While the progression of the digits of the various players across the windows 71 is not visible to all persons in an audience grouped about the apparatus, the whole audience, and the players as well, are advised of the relative progress of the players during each play by the travel of the small automobile 29 about their respective race tracks.

Figures 7 and 8 illustrate another advantage of my invention namely its use as a table top. In these figures it will be seen that the box like structure 10 is inverted to place the imperforate bottom 11 uppermost. The inverted apparatus is now set in a table frame 72 fitted with the ordinary table legs 73. In this position the device may be used in the same manner as any ordinary table, while, to arrange it for playing, there needs be reversal of the apparatus in the frame 72.

While I have illustrated and described the preferred embodiment of my invention, it will be obvious that one skilled in the art may make modifications thereof without departing from the spirit of the invention. I wish, therefore, not to be restricted to the precise embodiment shown, except in so far as the same is limited in the appended claims.

I claim:

1. In a toy, the combination with a suitable frame, of a pair of spaced spindles mounted therein, a sprocket fixed on each spindle, an endless chain connecting said sprockets, a toy image fixed at a given point

to each chain, hand operated elements for rotating said spindles and chain, a rotatable counting wheel, means indicating a point fixed with relation to said counting wheel, 5 and gearing whereby the counting wheel is rotated from one of said spindles.

2. In a toy, the combination with a suitable frame, of a pair of spaced spindles mounted therein, a sprocket fixed on each 10 spindle, an endless chain connecting said sprockets, a toy image fixed at a given point to each chain, hand operated elements for rotating said spindles and chain, a rotatable counting wheel, means indicating a point 15 fixed with relation to said counting wheel and reducing gearing whereby the counting wheel is rotated from one of said spindles.

3. In a toy, the combination with a suitable frame, of a pair of spaced parallel 20 spindles journaled therein, a pair of sprocket wheels of equal radius fixed one to each spindle, an endless chain connecting said sprocket wheels, a toy image secured to said chain at a given point thereon, a crank 25 shaft, multiplying gearing whereby one of said spindles is driven from the crank shaft, a numbered counting wheel, means indicating a position fixed with relation to the numbers carried on the counting wheel, and reducing gearing whereby said counting wheel 30 is rotated by one of said spindles.

4. In a toy, the combination with a suitable frame, of a plurality of sets of rotatable hand operated apparatus, each of said sets 35 comprising a stud travelling in a circular path, a signal to be operated, and mechanism for operating the signal comprising a thrust

bar operatively connected to the signal, a plurality of parallel links of equal length each pivoted at its forward end to the frame 40 and at its rear end to said thrust bar and each positioned with one of its edges forming a chord of the circle described by one of said studs.

5. In a toy, the combination with a suitable frame, of a pair of standards spaced apart upon the frame, said standards being provided with opposed vertical guideways, a guide-block movable in each guideway, a signal bar extending from one standard to the 50 other and connected to said guide-block, a trigger in each standard for supporting the signal bar and guide box in an elevated position, a plurality of sets of hand operated apparatus and mechanism operatively related to each of said sets and so arranged as to be operable by any one of said sets to trip said trigger and permit the signal bar to drop.

6. In a toy, the combination with a frame, 60 of a pair of spaced spindles mounted therein, a sprocket on each spindle, an endless chain connecting said sprockets, a toy image connected to said chain, means for actuating said chain, a pair of standards, and a signal bar extending between said standards, 65 means for supporting said bar in elevated position on said standards, means actuated after a predetermined travel of said chain after releasing said signal bar. 70

In testimony whereof I have affixed my signature.

ERNEST G. SCHREYER.
